UNITED STATES PATENT OFFICE.

DIAMOND DIAMANTIDES, OF CANONSBURG, PENNSYLVANIA.

METHOD OF AND APPARATUS FOR RAISING SUNKEN SHIPS.

Application filed January 10, 1922. Serial No. 528,259.

To all whom it may concern:

Be it known that I, DIAMOND DIAMANTIDES, a subject of the King of Greece, and resident of Canonsburg, in the county 5 of Washington and State of Pennsylvania, have invented certain new and useful Improvements in Methods of and Apparatus for Raising Sunken Ships, of which the following is a specification.

10 This invention relates to a method of and apparatus for raising sunken ships, and has for an object the provision of novel means whereby an under water boat in the nature of a submarine may be attached to a sunken 15 ship or hull and made buoyant in order that it will lift the said sunken ship or hull.

In practice it is preferable to employ two or more under water crafts to be hereinafter referred to as submarines, and preferably 20 one or more such submarines should be attached to the sunken ship or hull of a ship, to be hereinafter referred to as a hull, the submarines having a novel construction which will cause them to lie close to the 25 sides of the hull being raised, while the work of coupling or fastening the submarines to the hull is being carried on.

It is a further object of this invention to 30 provide a novel hull penetrating device adapted to be associated, in part, with the means for fastening or coupling the submarines to the hull.

It is a further object of this invention to 35 provide submarines adapted to communicate with a master ship or pilot which will float in proximity to the hull to be lifted, in order that communication may be established between the two for the purpose of signaling and for removing water from the 40 submarine when the submarine is to be lightened to cause it to float.

With the foregoing and other objects in view, the invention consists in the details of construction, and in the arrangement and 45 combination of parts to be hereinafter more fully set forth and claimed.

In describing the invention in detail, reference will be had to the accompanying drawings forming part of this application 50 wherein like characters denote corresponding parts in the several views, and in which—

Figure 1 illustrates a sectional view of the pilot ship, hull and the submarines in operative relation to one another;

55 Figure 2 illustrates a top plan view of the hull and the submarines;

Figure 3 illustrates an enlarged detailed sectional view of one of the submarines;

Figure 4 illustrates an enlarged detailed sectional view of the hull penetrating apparatus;

Figure 5 illustrates an enlarged detailed sectional view of the coupling between the submarine and the hull; and

Figure 6 illustrates an enlarged detailed sectional view of a valve for the tool chamber of a hull penetrating apparatus.

While it is to be understood that any of the more improved methods for boring or penetrating steel may be employed for producing the holes in the hull to receive the couplings by which the submarines are connected to the hull, one example of the means for accomplishing that result is illustrated, and it comprises a plurality of devices 75 adapted to bore holes in the hull, the said devices being stationed on the submarines, as will presently appear.

In carrying the invention into practice, submarine boats are employed, each comprising a hull 10 having a water or ballast compartment 11 extending along the outer side, or at that side remote from the hull of the ship to be raised. This provision of weight on the outside of the submarines insures that their inner sides, or those that are in proximity or contact with the hull, will be forced toward the hull by the weight of the water.

The submarines are further provided with 90 diagonally disposed corners 12 at the top next to the hull in order that there will be no leverage afforded between the submarine and the hull at the top of the deck of the submarine.

95 Each submarine is provided with suitable compartments 13, 14 and 15 to form working chambers and chambers for ballast, but the internal arrangement of the said submarine may be variously modified to suit particular 110 requirements, in so long as the distribution of the weight is maintained approximately as indicated and the configuration of the submarine is observed.

The submarine has a plurality of chambered members 16 suitably supported in the working chamber and each said member 16 has a passage 17 therethrough which is controlled by a screw valve 18 working in a threaded bushing 19, as shown in Fig. 6. 110 The passage 17 is intended to receive the hull penetrating element, which is here

shown as a drill 20, the shank of the drill extending through the channel 17 and being provided with suitable means for its rotation or operation, according to the type of tool employed. It would be possible to substitute an electric torch or other device of that kind for boring the holes in the hull, but that is a detail of construction which may be changed to suit the requirements.

- 10 When a hull boring tool is to be applied to the channel, the valve is open after the tool has been inserted in the aperture 17 to prevent the inflow of water, and thereafter, the tool may be operated until the hole is formed in the hull. The boring tool can then be removed and a coupling 25^a for attaching the submarine to the hull will be inserted in the channel and forced into the aperture of the hull so that the hull and 15 the submarine will be coupled together. Of course there will be a plurality of couplings between the submarine and they may be of large or small size, according to the weight 20 to be lifted.
- 25 Where a very large hull is to be raised, it may be desirable to employ two or more submarines on each side of the hull, but as the construction of the submarines will be practically the same as that described, 30 one skilled in the art will understand how the submarines could be brought into operative relation to the hull to acquire the results indicated.

The pilot or master boat 21 will be in 35 communication with the submarines through the pipes or hose 23 in order that the pumps of the ship may be operated to remove water from the submarines when they are to float, and a cable or other conductor 24 may be 40 employed between the ship and a submarine for the purpose of signaling, and of course, these devices will be supplied for each submarine that is coacting with the master ship, when desired.

45 The aperture 17 of the member 16 has a lining or bushing 25 which extends beyond the end of the said member through the metal plates of the submarine, and the boring tool and the coupling element will be 50 of a size to fit within this lining or bushing to facilitate the work of the operators.

In the operation of the apparatus, when 55 the water ballast is being removed from the submarine, the ballast that is in the compartment 11 will not be disturbed, as its presence is desirable for creating weight at the outer edges of the submarine, in order that the sides of the submarine next to the hull will be forced into position against the 60 sides of the hull.

Furthermore, when the chambers of the submarine are to be relieved of the water ballast, a provision is preferably made for operating the pumps that remove the water 65 from the said compartments by power sup-

plied by the submarine, whereas the said compartments may be filled with air pumped by the pilot vessel through hose, as will be apparent by one skilled in the art. It is to be understood furthermore that the boring bit or drill will be practically the diameter of the opening in the member 16, and that the connection between the said submarine and the hull which enters the aperture in the member 16 as a substitute for the drill will be substantially of the same diameter, in order to avoid leakage and to employ connections which are strong and durable.

70 Preferably when the boring apparatus is being operated, it should be directed diagonally upward in order that the hole in the hull will form a better anchorage for the connecting rod when it is substituted for the drill.

75 The submarine might also be supplied with jacks which could be interposed between the side of the hull and the said submarine for the purpose of forcing the same apart when the fastenings are to be disconnected from the said hull, or for other purposes. As has been indicated, the pilot ship 80 on the surface may have connections with the submarine for signaling by telephone or otherwise, and connections for pumping air, and such conductors of electricity as will 85 be necessary to supply electric current to 90 the apparatus of the submarine.

95 It is furthermore desirable to at times have two vessels on the surface, one the pilot ship with connections to the submarine as above indicated, the other vessel to be 100 used to assist in bringing the submarines into operative contact with the hull.

I claim:

1. In an apparatus for raising sunken ships, a submarine having its upper inner edge diagonally disposed with relation to a hull to be raised, partitions in the submarine forming chambers, a ballast chamber extending longitudinally of the submarine at its outer edge, chambered elements extending through the diagonally disposed plate of the submarine, means for controlling the chambers of the elements, boring tools adapted to be applied to the said chambered elements and extending therethrough for operating on a hull, and coupling bars adapted to be substituted for the boring tools in the chambered elements for coupling the submarine to the hull.

110 2. A device for raising sunken vessels 120 comprising a submarine having a weight on its side remote from the hull to be raised, the sheathing of the submarine having a diagonally disposed upper corner next to the hull, and means for connecting the hull to 125 the submarine at the diagonally disposed portion of the said submarine.
